UNITED STATES PATENT OFFICE.

WILLIAM N. JOHN, OF MILWAUKEE, WISCONSIN.

REVERSIBLE TAPPING-CHUCK.

1,381,197.

Specification of Letters Patent. Patented June 14, 1921.

Application filed January 19, 1920. Serial No. 352,455.

To all whom it may concern:

Be it known that I, WILLIAM N. JOHN, a citizen of the United States, and resident of Milwaukee, in the county of Milwaukee and State of Wisconsin, have invented certain new and useful Improvements in Reversible Tapping-Chucks; and I do hereby declare that the following is a full, clear, and exact description thereof.

10 My invention relates to new and useful improvements in reversible chuck devices adapted for association with the drive spindle of a drill press or similar mechanism for performing thread cutting and like operations, my device being more particularly of that type wherein the tool is automatically reversed upon drawing it from the hole.

It is more particularly an object of my invention to provide an exceedingly compact gear arrangement whereby a maximum reduction of speed may be procured in reversing the direction of rotation of the tool member.

20 It is further my object to provide a gripping arrangement for the tap or other tool member employed which permits a full float action of the tool to adapt itself to the hole to be tapped or threaded, and wherein the element of wear is reduced to a minimum.

30 A still further object resides in the provision of an improved arrangement for procuring a positive discharge of oil or other lubricating fluid against the tool in its cutting action.

35 With the above and other objects and advantages in view, which will be apparent as the description proceeds, my invention resides in the novel features of construction, combination and arrangement of parts, which will be hereinafter more particularly described and defined by the appended claims.

In the accompanying drawings:

40 Figure 1 is a vertical sectional view through a reversible chuck structure embodying my invention.

Fig. 2 is a plan view of the gear casing, with the cap portion thereof removed.

45 Fig. 3 is a transverse sectional view on the line 3—3 of Fig. 1.

Fig. 4 is a transverse sectional view on the line 4—4 of Fig. 1, and

50 Fig. 5 is a transverse sectional view through the tool gripping members on a plane indicated by the line 5—5 Fig. 1.

Referring now more particularly to the accompanying drawings, I provide a cup-shaped gear casing formed of a pair of mating sections 10 and 11 respectively, said sections being connected at their upper portion 60 by the depending wall of a cap member 12 which is threaded thereon, the cap member forming the top of the casing and carrying a central bearing portion 13 in which is journaled the hub 14 of an internal gear 65 ring 15 which is of a diameter slightly less than the internal diameter of the casing. The shank member 16 is threaded in the hub to engage in the socket of the rotating spindle of the drill press or similar mechanism. 70 The lower ends of the mating casing sections are connected by a ring 17 threaded on sleeve extensions 18 thereof, and a bearing sleeve 19 is mounted in said sleeve extensions and receives a shaft 20 which extends 75 through the casing and is slidable in the hub 14. This shaft 20 carries suitable tool gripping means, as will be later specifically described. A gear 21 is loosely mounted on the shaft 20 in the lower portion of the 80 casing and this gear meshes with idler gears 22 carried by the lower portion of stub shafts 23 mounted in inward bearing extensions 24 on the wall of the casing, the upper ends of said shafts 23 carrying gears 25 85 meshing with the internal gear 15 whereby to provide a drive connection between the upper member 14 and the loose gear 21. A clutch member 26 is mounted on the shaft 20 between the loose gear and hub member and 90 is selectively engageable with clutch portions formed on the members.

Thus, when the shaft 20 is shifted inwardly as will occur when a tool carried thereby is pressed against its work, a direct 95 drive will be afforded from the hub member to the shaft 20, and when the shaft member 20 is shifted outwardly, a reverse drive at a greatly increased speed will be procured through the internal gear 15, gears 22 and loose gear 21 to thus procure withdrawal of the tool from the work at a rapid speed. The gear casing is held from rotation by an arm 27 carried on a bolt 28 threaded on the side of the casing, said arm 100 being adapted to engage the frame of the drill press or other structure with which my device is associated.

105 A cylindrical tool receiving head 28 is formed on the lower end of the shaft 20 and 110

is provided with a transverse slot there-
through in which is loosely mounted upper
and lower blocks 29 and 30 respectively, the
lower block being provided with a depend-
ing portion which extends through the bot-
tom of the head. The upper block is provided
with a squared recess 31 for receiving the
usual squared upper end of the shank of a
tap *t* or similar tool member, while the
lower block 30 is provided with a passage
for receiving the rounded portion of the
shank, a set screw 32 being threaded in the
block 30 to bind the shank therein. The
block 30 thus serves merely to hold the tool
member within the head, while the rotative
driving impulse of the tool member is im-
parted thereto by the engagement of its
squared upper end in the correspondingly
squared aperture of the block 29 which is
loosely held against rotation by abutment
with the sides of the slot of the head. A
floating drive is thus afforded for the tap,
whereby it may automatically adjust itself
to properly centered position with respect to
the hole to be threaded, and inasmuch as the
squared end of the tool member will be en-
gaged on all four sides by the recess of the
block 29, a positive drive is effected with a
minimum amount of wear, in contradistinc-
tion to those arrangements wherein the drive
action is imparted to the tool member
through a screw thread binding engage-
ment.

To insure positive discharge of oil or
other coating fluid onto the tool member, a
casing 34 is loosely disposed about the work
receiving head, the wall of the casing being
held spaced from the head by an apertured
flange 35 in its lower portion and by a de-
tachable upper closure member 36 of the cas-
ing. A nipple 37 extends from the casing
for connection with a suitable fluid supply
tube 38 and the bottom of the casing is pro-
vided with an aperture slightly larger than
the reduced extension of the block 30 where-
by cooling fluid discharged into the casing
will be directed downwardly in an annular
stream about the working portion of the tool
member, the tool head rotating freely within
the casing and supporting the same.

I have thus provided a comparatively sim-
ple and highly efficient reversible tapping
chuck which possesses decided advantages of
economy, strength and durability.

While I have shown and described a pre-
ferred embodiment of my invention, it will
be appreciated that various changes and
modifications of structure may be employed
to meet differing conditions of use and

manufacture, without departing in any man- 60
ner from the spirit of my invention.

What is claimed is:

1. A chuck device of the class described
comprising a gear casing including a pair
of mating sections forming a cup shaped 65
body, a cap member threaded on the mouth
portions of said sections, bearing extensions
at the bottoms of said sections, means secur-
ing said extensions together, a bearing sleeve
in said extensions, a tool carrying shaft 70
slidable in said sleeve, an internal gear hav-
ing its hub portion journaled in said cap
member, means for driving said internal
gear, a counter shaft journaled in the casing,
a gear loose on said slidable shaft, pinions 75
on the counter-shaft meshing with said loose
gear and the internal gear, a clutch mem-
ber on the slidable shaft between the gears,
and coacting clutch portions carried by the
gears. 80

2. In a chuck device of the class de-
scribed, a driven shaft, a head on said shaft,
means for securing a tool in said shaft head,
a casing loosely disposed about said shaft 85
head and provided with an aperture in its
bottom to direct fluid along the tool carried
by the head, and a liquid supply means for
the casing. 90

3. In a chuck device of the class de-
scribed, a driven shaft, a head on said shaft,
means for securing a tool in said shaft head,
a cup shaped casing member adapted to re-
ceive said head, a closure for said casing
member, said casing member and closure
having rotative bearing engagement with
the head and said casing being provided
with an opening in its bottom, and a fluid
supply tube extending from said casing. 95

4. A chuck device of the class described,
a drive shaft, a head portion on said drive 100
shaft provided with a transverse slot, a tool
member having a rounded shank portion ter-
minating in a squared extremity and inserti-
ble in the slot of the head portion, a block
transversely slidable in the slot of the head 105
portion and provided with a squared aper-
ture for loosely receiving the squared ex-
tremity of the tool shank, a collar loosely
disposed in the slot of the head below said
block and adapted to receive the tool shank, 110
and means for binding the shank in the
collar. 115

In testimony that I claim the foregoing I
have hereunto set my hand at Milwaukee, in
the county of Milwaukee and State of Wis-
consin.

WILLIAM N. JOHN.
